US00D931101S

(12) **United States Design Patent** (10) Patent No.: **US D931,101 S**
Tse et al. (45) Date of Patent: ** *Sep. 21, 2021

(54) **CLOSURE**(71) Applicant: **Berlin Packaging, LLC**, Chicago, IL (US)(72) Inventors: **Kieron Tse**, Mt. Prospect, IL (US); **Brett Niggel**, Chicago, IL (US); **Sharwari Puskala**, Chicago, IL (US); **Andrew Sanguinet**, La Grange Park, IL (US)(73) Assignee: **Berlin Packaging, LLC**, Chicago, IL (US)

(*) Notice: This patent is subject to a terminal disclaimer.

(**) Term: **15 Years**(21) Appl. No.: **29/638,949**(22) Filed: **Mar. 2, 2018**(51) LOC (13) Cl. **09-07**

(52) U.S. Cl.

Much Shelsit, P.C.

(57) **CLAIM**
The ornamental design for a closure, as shown and described.

DESCRIPTION

FIG. 1 is a front left side perspective view showing the new design for a closure;
FIG. 2 is a underside perspective view thereof;
FIG. 3 is a left side view thereof;
FIG. 4 is a right side view thereof;
FIG. 5 is a front elevation view thereof;
FIG. 6 is a rear elevation view thereof;
FIG. 7 is a top plan view thereof;
FIG. 8 is a bottom plan view thereof;
FIG. 9 is a rear left side perspective view of the closure of FIG. 1 shown with a pour lid feature in the open configuration;
FIG. 10 is a front left side perspective view thereof;
FIG. 11 is a underside perspective view thereof;
FIG. 12 is a left side view thereof;
FIG. 13 is a right side view thereof;
FIG. 14 is a rear elevation view thereof;
FIG. 15 is a front elevation view thereof;
FIG. 16 is a top plan view thereof;
FIG. 17 is a bottom plan view thereof;
FIG. 18 is a front left side perspective view of the closure of FIG. 1 shown with a sift lid feature in the open configuration;
FIG. 19 is a front right side perspective view thereof;
FIG. 20 is a rear right side perspective view thereof;
FIG. 21 is a underside perspective view thereof;
FIG. 22 is a left side view thereof;
FIG. 23 is a right side view thereof;
FIG. 24 is a front elevation view thereof;
FIG. 25 is a rear elevation view thereof;
FIG. 26 is a top plan view thereof; and,
FIG. 27 is a bottom plan view thereof.

The broken lines depict portions of the closure that form no part of the claimed design.
